CONTAINER

Kenneth L. Murray, Evanston, Ill., assignor to
 Beatrice Creamery Company, a corporation of
 Delaware

Application January 2, 1932, Serial No. 584,314

7 Claims. (Cl. 229—23)

The invention relates to improvements in water-proof paper containers and the primary object of the invention is to provide a convenient, economical, efficient and attractive appearing container that may be used for packaging and transporting ice cream in its usual semi-solid condition or other analogous food products that may partake of a semi-solid or partly liquid form, and which is particularly adapted to be easily removed from the food package while the contents thereof are in solid or semi-solid form in order that the contents of the package may be completely freed on all but one side thereof, at least, from the package with ease and facility to permit the contents to be cut into a plurality of slices or other smaller portions in serving the same.

A further object of the invention is to provide an improved form of paper container for frozen ice cream and analogous food products that may be removed from the body of the material within the package without disturbing the form or body of the contents of the container to assist in subdividing the food body within the container for convenience in serving.

It is a further object of the invention to generally improve the form, construction and mode of operation of water-proof containers made of paper or thin fibrous materials that are especially adapted for packaging frozen ice cream and analogous food products.

It is a further object of the invention to provide an improved two-part container made of paper or other analogous or water-proof paper in the form of two telescoping integral blanks that may be assembled for completing the package and disassembled for the purpose of freeing the contents of the package in the form of a block or loaf for accessibility.

It is a further object of the invention to provide an improved form of integral blank comprising a body portion and a plurality of foldable flaps adapted to be folded into the form of a closed container and retained in such condition by a telescoping tube-like envelope which is adapted to surround the normal side walls of the carton.

It is a further object of the invention to provide a composite or two part, knock-down container for food products consisting of a collapsible inner carton formed of an improved blank of water-proof paper or analogous material having a body portion and a plurality of foldable flaps of a form capable of being set up or expanded to form a collapsible closed, substantially

liquid proof carton, and being held in its set up or assembled material containing form only by a closely fitting, telescopic, tube-like, detachable outer sleeve, the removal of which will freely permit the opening of the inner carton to a substantially flat condition for exposing and serving the contents thereof.

Other objects of the invention will appear from the following description of the invention which is directed to the preferred embodiment thereof as illustrated in the accompanying drawings forming a part of the specification, the novel features being set forth more specifically in the appended claims.

In the said drawings: 15
 Fig. 1 is a perspective view of a complete composite container embodying the invention.

Fig. 2 is a view similar to Fig. 1 showing the upper closure flaps of the container in open or expanded condition ready for the insertion of 20 the material which the container is designed to receive.

Fig. 3 is a perspective view of the tubular cover or shell detached from the composite device of Figs. 1 and 2 and Fig. 4 is a sectional view approximately on the plane determined by the lines 4—4 of Fig. 3. 25

Fig. 5 is a plan view of the blank showing the manner in which it is formed and scored to produce the tubular cover open at both ends in the 30 form of a frustum of a pyramid for receiving and retaining the inner formed and folded blank of the container.

Fig. 6 is a plan view of the complete blank showing the manner in which it is scored and 35 also cut to form an irregular outline to produce the required panels forming the sides of the container when folded as well as the integral bottom part thereof and to which certain described flaps are integrally attached for forming the container into a complete closure.

Figs. 7 and 8 are vertical detail sectional views taken upon planes at right angles to each other substantially as defined by the lines 7—7 and 8—8 of Figs. 8 and 7, respectively, the view in 45 Fig. 8 being also defined as taken on the vertical plane indicated by the lines 8—8 in Fig. 1.

Fig. 9 is a detail sectional view through the composite device of Figs. 1, 2, 7, and 8, the view being substantially on the horizontal plane defined by the line 9—9 of Fig. 7 looking in the direction indicated by the arrows. 50

Figs. 10, 11, and 12 designate a modified and somewhat simplified form of a blank foldable into condition as an economical substitute for 55

the inner container blank of Fig. 6, the expanded blank being shown in plan in Fig. 10 while Fig. 11 is a vertical sectional view through the container formed by completely folding the blank to its operative condition but without the cover or shell of Fig. 3, and Fig. 12 is a horizontal section taken on the line 12-12 of Fig. 11 looking in the direction indicated by the arrows.

My invention is comprised in the form and manner of assembling the especially prepared blanks appearing in their expanded or flat form as shown in Figs. 5 and 6. Since the blank illustrated in Fig. 6 is the one that is designed to receive the contents of the package or container and since the container is particularly adapted for the packaging of ice cream or analogous food products that will contain moisture, I prefer to use a medium grade of paraffined paper board although it would be apparent that various creasible water-proof materials may be used in making the blank for the inner portion of the container.

Although it will be apparent that the invention might take the form of a perfect cube or a parallelopiped whose angles are all right angles, I moreover prefer, for various reasons that will appear, in the manufacture of my improved container for ice creams and other dairy products as well as food products such as oysters, pickles and the like, to make the container in the general form of an inverted frustum of a pyramid, that is, having the smaller end of the container toward the bottom as in a form of previously well-known paper cartons or buckets heretofore used for like purposes as herein mentioned.

Since my improved container comprises two separate co-operating portions, this frusto-pyramidal or downwardly tapering form of the side walls of the package is advantageous in retaining the two parts of the container together in their assembled operative relations, particularly if it should be desired to attach a bail or some other suitable carrying means to the outer or upper end of the tubular cover portion of the container; therefore, the complete cut and scored blank as illustrated in Fig. 6 and designated generally by the reference character 10 will consist in a general way of two large parallel side walls or panels designated by reference characters 11 and 12 defined by the scored lines and connected by the integral bottom portion 13, also defined by scored lines as illustrated in Fig. 6 upon which it is desired that the blank shall be creased for folding the blank expanded container blank.

By further reference to Fig. 6 it will be seen that the integral blank body is extended longitudinally and laterally from the panels 11, 12 to form certain foldable portions and flaps to complete the container; for example, on the two opposite sides of the panel 11, there are integral panels 14, 15 and on the sides of the panel 12 there are similar laterally extending panels 16, 17 cut to the form and purpose illustrated in Fig. 6. The material of the blank at substantially the outer edges of the panels 14 and 15 will be extended beyond the scored lines forming the outer ends of the panels 14, 15 as illustrated by the dotted lines in Fig. 6 and likewise beyond the scored line defining the upper end of the panel 11, the material of the blank body will also be extended as an integral part of the blank, and notches 18 and 19 provided extending down to the scored lines which define the outer boundaries of the parts 11, 14, and 15, thus pro-

ducing a substantially rectangular upper end closure flap 20 integral with the panel 11 and the irregularly shaped flaps 21, integrally connected to the panels 14 and 15 and carried thereby for co-operation with the other described flaps for forming a closure at the upper end of the container.

The blank 10 is further suitably notched as illustrated at 22, 23 to produce foldable bottom flaps formed integrally with the bottom portion 10 13 of the container as designated by the reference characters 24, 25 and these flaps 24, 25 will be severed from their respective contiguous portions 14, 15, 16, and 17 by the short cuts as designated at 26 thus putting the flaps in condition 15 for folding at an angle to the bottom member 13 when the blank 10 is assembled to its set up condition in forming the complete container.

The before-mentioned substantially rectangular top flap 20 will be provided with a median 20 slit 27 designed to act as a keeper or retaining means for a protruding tongue 28 formed as an integral part of the portion 28 at one extremity of the panel 12.

Referring to the blank for forming the outer 25 or tube-like cover as illustrated in Fig. 5, it will be seen that this consists of an integrally extending strip designated generally by the reference character 40 and it will also preferably be formed of a fairly stiff, substantial grade of paper or analogous material, paraffined or otherwise suitably treated to give it waterproof characteristics when intended to handle the before mentioned food products as ice cream and the like.

41 and 42 are side panels of the cover blank designed in the completed container, as will be seen, to overlie and be substantially co-extensive with the panels 11, 12 of the inner container, and they are connected by the intermediate narrower 40 panel 43 and to the terminal portions or panels 44, 45 respectively, all these portions from 41 to 45 inclusive being separated by suitably scored lines as illustrated so as to be foldable in relation to each other to form the assembled cover 45 member of the container as illustrated in Figs. 1 and 4.

As before indicated, the foldable sheet 40 is adapted to make a retaining cover for the package or container that will give it permanent 50 form and retain the package in that condition; and to that end, the overlapping panels 44, 45 must be substantially secured together which may be done when they are brought to the form illustrated in Figs. 1, 3, and 4 by pasting them 55 together using a suitable glue or adhesive or they may be permanently stitched together or otherwise suitably secured so that this outer sleeve or cover, which may be suitably decorated for ornamental or aesthetic or advertising purposes, may be a substantial supporting device capable, if a bail or other carrying means be attached thereto, of supporting the package or container for transportation.

The complete container in condition for receiving ice cream or other analogous material will be prepared and assembled in the manner illustrated in Fig. 2. The detail sectional views, Figs. 7, 8, and 9, most clearly illustrate the manner and sequence of folding the various panels and flaps of the inner container blank, from which it will be seen that the inner container blank 10 of Fig. 6 will be formed into a cup-like shape by bending the side panels 11 and 12 almost to the right-angle position on the scored lines 50, 51, 75

The narrower side panels 14, 15, 16, and 17 will then be folded on their respective scored lines 52, to 55 inclusive, so that they will be brought to an overlapping position to form the end substantially vertical connecting panels of the container serving as the connecting end walls between the substantially vertical side walls 11, 12 of the container portion proper.

In laying out the respective sizes of the foldable portions 14, 15, 16, and 17, these will preferably all be of a like dimension except that provision may be made in cutting the material to allow for the space that is consumed in folding the panels around each other at the vertical corners due 15 to the thickness of the material that is utilized.

In the sectional views through these substantially vertical composite end walls of the folded inner container blank as illustrated in Figs. 7 and 9, the panels 16 and 17 are shown as folded inwardly to a substantially right-angular position on the lines of fold 54 and 55 and the co-operating panels 14, 15 are then folded over on fold lines 52, 53 to lie flat upon the outside of the panels 16 and 17. This will result in the formation of a closed container with the exception of the open top since the flaps 20, 21 and 28 will then be in the condition illustrated in Fig. 2, but the inner container blank 10 is not designed to be permanently secured in its thus folded or set-up condition and it will be apparent that in this condition the short flaps 24, 25 at the ends of the bottom portion 13 will still extend substantially in the plane of the bottom 13. However, in this position the inner container is in condition for insertion into the expanded and set-up outer cover device 40 and this will be accomplished by merely bending the short flaps 24 and 25 upwardly and dropping the inner container blank thus folded into the enlarged upper end 40 of the holding cover 40 (Fig. 3) until the parts reach the position illustrated in Figs. 1 and 2 when the container will be in condition for filling as it is illustrated in Fig. 2 after which the top flaps may be folded to the closed positions for 45 which they are adapted as illustrated in Fig. 1, the flaps at the narrower side ends being folded over flat upon the top of the contents of the inner package and the flap 20 next folded down on the overlapping flaps 21 after which the flap 28 may be brought to the closed position and the flaps locked in their closed position by the insertion of the flap 29 into the slot 27.

The above described manner of folding the inner container blank, Fig. 6, will result in the formation of an inner container within the tubular cover 40 that will present a substantially smooth inside surface with no projecting parts to the material within the container. This is an important consideration in the use of the container for various materials, especially should it be desired at any time to dispense said materials from the container in an ordinary manner as by dipping the same therefrom with a spoon or other implement since with my improved inner container folded as described there will be no projecting flaps on the interior to interfere with the removal of the material from the container. When the container is used for the reception of ice cream and analogous food products the fact that it may at some stage in its use contain some liquid, the fact that all of the joints of the inner container blank 10 will be covered by overlying thicknesses of the water-proof material when set up in the manner described will be apparent.

An important feature of my improved container resides in its construction adapting the same to serve as an economical and substantially perfect receptacle for food products if they melt and become liquid or partially liquid but which, at the same time, are desired primarily to be retained in a solid or semi-solid form and to be served in that condition as by cutting the same in cubes or slices, a procedure that has not heretofore been feasible with ice cream containers of the general character or class to which the invention is particularly adaptable, by providing a food bucket of the described character in which an inner container of a collapsible and expansible nature is held in its operative condition by the 15 slidable or telescoping cover and these parts interlocked together against separation by sliding apart in one direction while freely separable when one of the parts is relatively moved in relation to the other in the opposite direction to produce an 20 improved container especially for use in storing, transporting and serving frozen ice cream and analogous products which makes it possible to serve the same in a manner not heretofore attainable in which the outer cover may be readily 25 separable from the inner container and then leaving the inner container in condition to be freely opened with the block or loaf of food in a condition where it may be completely exposed on all except one side of the collapsible container 30 blank 10 upon which it may rest, by merely releasing the flaps 20, 21, and 29 and the flaps 14 to 17 inclusive which will permit the enveloping container member 10 to be restored to its substantially flat position as illustrated in Fig. 6 when 35 the block or loaf of food material still upon the flat blank if desired may rest upon a plate or platter for slicing or service in any other desired manner.

In Fig. 10 I show a container blank of special 40 construction like the blank illustrated in Fig. 6 with the exception that it is modified so as to leave off the one pair of the overlapping panels at the ends of the substantially vertical parts of the inner container, preferably the parts 16 and 45 17, since it is found that there are certain food products that may be handled in containers of this character in a substantially solid or semi-solid form where the question of providing a substantially liquid tight receptacle is not of paramount importance. In such containers the flaps 16 and 17 may be omitted from the sides of the panel 12 as illustrated in Fig. 10 in which the reference character 60 represents the entire blank. While the blank 60 thus constructed without the flaps 16 and 17 is not the preferred form 55 the invention should take where materials that are liquid or likely to become liquid are to be handled, this modified form of inner container blank 60 may be used, and when so employed is slightly easier to fold and will result in some economy in the initial cost of production since in cutting the part 60 from a sheet of material, the various sections cut from the sheet of material 60 may be staggered and some stock saved.

In order that the invention might be understood, the details of the preferred embodiment have been set forth and described with particularity but it is not desired to be limited to the 70 various details except as set forth in the claims as defining the scope of the invention.

I claim:

1. A container structure of the two-piece type adapted to be formed into a substantially liquid- 75

tight closed receptacle comprising an inner carton blank cut to provide a bottom wall having relatively short, integral opposing flaps to which is integrally attached opposing foldable side walls 5 with one of said foldable side walls carrying integral foldable end walls, a plurality of foldable top closure flaps, one of which is integral with and carried by the respective extremities of each of the said side and end walls at the ends thereof 10 opposite the bottom wall and being adapted to be folded to form a closure for the top of the container when the said side walls are folded to a substantially right-angular position in relation to the bottom wall and when the said end walls 15 are folded to substantially right-angular relations to the respective side walls to form connections therebetween, and an open-ended tube-like cover portion adapted to telescopically receive and closely surround the folded side and end walls of the aforesaid container blank with the said relatively short bottom flaps interposed 20 between the end walls and the cover portion when the said side and end walls thereof are folded in the manner described on the bottom portion and inserted within the cover portion to 25 form a container structure in which the inner carton blank is held in assembled condition only by the tube-like cover portion and the top flaps and thus may be readily opened for the serving 30 of the contents and still be substantially liquid proof when assembled with the tube-like cover portion.

2. A container structure of the two-piece type adapted to be formed into a substantially liquid-tight closed receptacle comprising an inner carton blank cut to provide a bottom wall having relatively short, integral opposing flaps to which is integrally attached opposing foldable side walls, carrying two pairs of integral, foldable end walls, 35 a plurality of foldable top closure flaps integral with and carried by the respective extremities of the said side walls and by two of the end wall portions at the ends thereof opposite the bottom wall and being adapted to be folded to form a closure for the top of the container when the said side walls are folded to a substantially right-angular position in relation to the bottom wall and when the said end walls are folded to overlap each other and in substantially right-angular 45 relations to the respective side walls to form connections therebetween, and an open-ended, tube-like cover portion adapted to telescopically receive and closely surround the folded side and end walls of the aforesaid container blank with the said relatively short bottom flaps interposed 50 between the end walls and the cover portion when the said side and end walls are folded in the manner described on the bottom portion and inserted within the cover portion to form a container structure in which the inner carton blank is held in assembled condition only by the tube-like cover portion and the top flaps and thus may be readily opened for the serving of the contents 55 and still be substantially liquid proof when assembled with the tube-like cover portion.

3. A container structure of the two piece type adapted to be formed into a substantially liquid-tight closed receptacle comprising an inner carton blank cut from a sheet of waterproofed paper or analogous material to provide a bottom wall of rectangular form having relatively short, integral opposing flaps to which is integrally attached opposing foldable side walls, one of said 65 foldable side walls carrying integral foldable

end walls, there being a plurality of foldable top closure flaps integral with and carried on the extremities of the said side and end walls at the ends thereof opposite the bottom wall and being adapted to be folded to form a closure for the top 5 of the container when the said side walls are folded to angular positions in relation to the bottom wall and when the said end walls are folded in angular relation to the respective side walls to form connections therebetween, the said respective side and end walls each being shaped in the form of a quadrilateral with the respective longitudinal side edges thereof diverging outwardly from their extremities adjacent the bottom wall whereby when the said end and side 10 walls of the blank are folded in the manner described, to form a container shell in the form of an inverted, truncated pyramid with the smaller end closed by the bottom wall of the aforesaid blank and the enlarged upper end of the container adapted to be closed by the aforesaid foldable top closure flaps, and an open-ended, tube-like cover portion having also the form of a truncated pyramid and being adapted to telescopically receive, closely surround and support the 15 folded side and end walls of the aforesaid container blank with the said relatively short bottom flaps interposed between the end walls and the cover portion when said walls thereof are folded in the manner described in relation to the bottom portion and inserted within the cover portion whereby to form a container structure in which the inner carton blank is held in assembled condition only by the tube-like cover portion and the top flaps and thus may be readily opened for 20 serving of the contents and still be substantially liquid proof when assembled with the tube-like cover portion.

4. A container structure of the two-piece type adapted to be formed into a substantially liquid-tight receptacle comprising an inner carton blank cut to provide a bottom wall with two opposite inwardly folding flaps and two opposite side walls with end wall extensions, a plurality of foldable overlapping top closure flaps carried by the side 40 and end walls at the ends thereof opposite the bottom wall and being adapted to form a closure for the top of the container when the inner carton blank is assembled, and an open-ended tube-like cover portion adapted to telescopically receive and closely surround the side and end walls of the inner carton blank when in assembled condition whereby the said blank is held in such assembled condition only by the said tube-like cover portion and the said top flaps are in a condition to be readily opened for the serving of the contents while being substantially liquid proof when in said assembled condition.

5. A container structure of the two-piece type adapted to be formed into a substantially liquid-tight receptacle comprising an inner carton blank cut to provide a bottom wall with two opposite inwardly folding flaps and alternate opposite side walls with end walls extending therefrom, a plurality of foldable top closure flaps carried by the 60 side and end walls at the ends thereof opposite the bottom wall and being adapted to interengage and form a closure for the top of the container when the inner carton blank is assembled, and an open-ended tube-like cover portion adapted to telescopically receive and closely surround the side and end walls of the inner carton blank when in assembled condition whereby the said blank is held in such assembled and closed condition only by the said tube-like cover portion 65

and the said top flaps in a condition to be readily opened for the serving of the contents upon the removal of the tube-like cover portion while being substantially liquid proof when in said assembled condition.

6. A container structure in the form of a substantially liquid-tight receptacle comprising an inner carton blank provided with a bottom wall and opposite bottom flaps and with opposite side walls with extending end walls, foldable and interengaging top closure flaps carried by the said side and end walls, the said inner carton blank being held in assembled and closed condition only by a detachable cover closely surrounding the said side and end walls and by said foldable top flaps whereby the container may be readily opened for the serving of the contents thereof upon the removal of the detachable side and end wall cover member and dissembling certain of the said walls and cover flaps thereof to expose the contents of the inner carton blank and still be substantially liquid proof when in assembled condition with the said side and end wall cover member.

7. A container structure in the form of a substantially liquid-tight receptacle comprising an inner carton blank cut to provide a bottom wall having inwardly folding flaps and integrally attached opposing, foldable side walls, foldable end walls carried by said side walls, a plurality of foldable top closure flaps carried by the respective side and end walls at the ends thereof opposite the bottom wall and being adapted to be folded together to form a closure for the top of the container when the inner carton blank is assembled, and a tube-like cover portion adapted to closely surround the folded side and end walls of the inner carton blank when in assembled condition whereby said blank is held in such assembled condition only by the said cover member and the said top flaps in a condition to be readily opened for the serving of the contents thereof upon the removal of the cover portion while being substantially liquid proof in said assembled condition in the cover portion.

KENNETH L. MURRAY.
